UNITED STATES PATENT OFFICE.

CORNELIUS DONKERSLEY, OF NEW YORK, N. Y.

RAILROAD-SWITCH.

SPECIFICATION forming part of Letters Patent No. 224,157, dated February 3, 1880.

Application filed June 14, 1879.

To all whom it may concern:

Be it known that I, CORNELIUS DONKERSLEY, of New York, in the county of New York and State of New York, have invented a new and useful Improvement in Railroad-Switches, of which the following is a specification, reference being had to the accompanying drawings, in which—

Figure 1, Sheet 1, is a top view of my improved switch. Fig. 2, Sheet 1, is a side view of the same, partly in section, through the line *x x*, Fig. 1. Fig. 3, Sheet 2, is a cross-section of the same, taken through the line *y y*, Fig. 1. Fig. 4, Sheet 2, is a longitudinal section of the same, taken through the line *z z*, Fig. 1.

The object of this invention is to furnish a switch for single-rail elevated railroads which shall be simple in construction, reliable in operation, convenient in use, strong, and durable.

The invention consists in a switch for a single-rail elevated railroad in which the switch-rails of the main and side tracks are attached to the frame of a truck the wheels of which run upon rails supported from the supporting structure of the said railway; in the combination of the ropes or chains, the wheels or drums, the three shafts, the two pairs of bevel-gear wheels, and the hand-wheel with the switch-truck and the frame-work and the movable rails; and in the combination of the ratchet-wheel provided with two notches, and the spring-pawl with the hand-wheel shaft, the switch-truck, and the switch-rails, as herein-after fully described.

A represents the rails of the main track, and *B* represents the rails of the side or branch track. The rails *A*, *B* are supported upon columns *C*, provided with guard-rails *D*. *a'* is the switch-rail of the main track, and which is made of such a length as to fit in between the adjacent ends of the rails *A* of the main track. *b'* is the switch-rail of the side or branch track, which is made of such a length as to fit in between the end of the rail *A* of the main track and the end of the rail *B* of the side or branch track.

The switch-rails *a'*, *b'* are attached to a truck-frame, *E*, in such positions that they may be moved into and out of line with their respective tracks by the reciprocating movement of the said truck-frame.

To the truck-frame *E* are pivoted the truck-wheels *F*, which run upon stationary rails *G*, attached to a frame-work, *H*. The frame *H* is designed to be attached to arms or brackets attached to the columns that support the rails *A*, *B*, or to other suitable supports.

To the ends of the truck-frame *E* are attached the ends of two ropes or chains, *I*, which make one or more turns around pulleys or drums *J*, attached to the shaft *K*, so that the truck *E*, *F* may be moved back and forth by turning the said shaft *K*. The shaft *K* works in bearings attached to the frame *H*, and to one of its ends is attached a bevel-gear wheel, *L*, the teeth of which mesh into the teeth of the bevel-gear wheel *M*, attached to the end of the shaft *N*. The shaft *N* works in bearings attached to the structure that supports the rails *G*, and is made of such a length that its other end may be out of the way of the cars as they pass along the track.

To the outer end of the shaft *N* is attached a bevel-gear wheel, *O*, the teeth of which mesh into the teeth of the bevel-gear wheel *P*, attached to the lower end of the short vertical shaft *Q*.

To the upper end of the shaft *Q* is attached a hand-wheel, *R*, for convenience in operating it. The shaft *Q* and the gear-wheels *O*, *P* are designed to be supported from the frame-work of the road, and are surrounded by a casing, *S*.

With this construction the switchman, by operating the hand-wheel *R*, can open the main track or the side track, as may be required. With this construction it will be observed that the switch-rail over which the train may be passing will be directly in line with the supporting structure of the road, so that there will be no side strain upon the truck or its supporting frame.

To the upper part of the shaft *Q* is attached a ratchet-wheel, *T*, provided with two notches to receive the engaging end of the pawl *U*, and which are formed in such positions as to receive the said pawl when the switch-rails are in position to open one or the other track, so as to hold the switch securely in position when adjusted, and so as to act as a stop to prevent the switch-rails from being carried past the line of the tracks.

The pawl *U* is pivoted to the casing *S* or its

supporting frame-work, and its engaging end is held forward against the ratchet-wheel T, ready to drop into its notches, by a spring, V, attached to the casing S or its supporting frame-work.

Having thus described my invention, I claim as new and desire to secure by Letters Patent—

1. A switch for a single-rail elevated railroad in which the switch-rails $a' b'$ of the main and side tracks, A B, are attached to the frame E of a truck the wheels F of which run upon rails G, supported from the supporting structure of the said rails A B, substantially as herein shown and described.

15 2. The combination of the ropes or chains I,

the wheels or drums J, the three shafts K N Q, the two pairs of bevel-gear wheels L M O P, and the hand-wheel R with the truck E F and the frame-work and the movable rails, substantially as herein shown and described.

20

3. The combination of the ratchet-wheel T, provided with two notches, and the spring-pawl U V with the shaft Q, the truck E F, and the switch-rails $a' b'$, substantially as herein shown and described.

CORNELIUS DONKERSLEY.
